Primary Examiner—Winifred E. Herrmann

Attorney, Agent, or Firm—Webster B. Harpman

[57] CLAIM

The ornamental design for a condiment dispenser, as shown and described.

DESCRIPTION

FIG. 1 is a front or rear elevational view of a condiment dispenser showing my new design;

FIG. 2 is a right or left side elevational view thereof;

FIG. 3 is a top plan view thereof;

FIG. 4 is a bottom plan view thereof; and

FIG. 5 is a modified form of my new design of FIGS. 1-4 wherein the top has a single aperture.

FIG. 1

FIG. 3

FIG. 4
